[57] CLAIM

The ornamental design for a programmable AM/FM
scanning radio receiver, as shown and described.

DESCRIPTION

FIG. 1 is a perspective view of a programmable
AM/FM scanning radio receiver showing my new
design;

FIG. 2 is a front elevational view;

FIG. 3 is a right side elevational view;

FIG. 4 is a rear elevational view;

FIG. 5 is a left side elevational view; and

FIG. 6 is a top plan view.

The bottom has no ornamental features and forms no
part of my design.

FIG.1

FIG. 2

FIG. 3

FIG.4

FIG. 5

FIG.6
